UNITED STATES PATENT OFFICE.

HERMANN DEUTSCH, OF BERLIN-GROSSLICHTERFELDE, GERMANY, ASSIGNOR TO
ADREMA MASCHINENBAU G. M. B. H., OF BERLIN, GERMANY.

ADDRESSING MACHINE.

Application filed October 22, 1920. Serial No. 418,863.

To all whom it may concern:

Be it known that I, HERMANN DEUTSCH, a citizen of the German Empire, residing at Berlin-Grosslichterfelde, Germany, have invented certain new and useful Improvements in Addressing Machines, of which the following is a specification.

My invention relates to addressing machines in which the printing-lever at the same time serves to feed the printing plates forward toward the particular section of a slide track, where the printing is to take place, and the general construction of which is well known to all persons familiar with the art.

The essential feature of my invention resides in so improving upon the construction of the addressing machines of the type known that the printing plates as they travel to the place of printing will automatically control a pad P in such a manner that as the printing-lever is depressed there will either be effected an impression or not by the printing plate after it has attained the place of printing. The control of the motion carried out by the pad P is effected in accordance with my invention by electrical means, projections disposed at the undersides of the printing plates and adapted to move within slots formed in the slide track, being caused to coact for this purpose with contact levers extending upwardly into said slots, which contact levers when operated serve to close electrical circuits which in their turn excite an electromagnet, by the control action of which the pad is moved into the printing position.

It will thus be understood that my improved device provides the possibility of subdividing the printing plates of an addressing machine by extremely simple means into a number of different groups by merely disposing the aforesaid projections of the plates in staggered positions relatively to each other, and then by operating the appropriate switches, to secure the advantage that as the printing plates travel through the addressing machine, only the printing plates belonging to a certain group or a number of particular groups will come to be automatically printed, while the printing plates belonging to the other groups disposed intermediate the printing plates about to be printed, will run inoperatively through the ma-

chine. For the purpose of accomplishing this particular object, the addressing machine constructed on the lines of my invention is provided with a number of parallel control circuits, within each of which there is arranged, besides a contact lever, a separate switch. It will be noted that the contact levers when encountering the projections arranged on the undersides of the printing plates are therefore only enabled to close the particular circuit, the hand switch of which is likewise in the closed position.

Within each of the control circuits of the addressing machine constructed in accordance with my invention, there is in addition interconnected a lamp, so that on a circuit being closed by the contact lever, the respective lamp thereof will flare up and thus serve as a signal for the person attending the machine showing that an impression is about to be made. The person attending the machine will moreover be enabled to learn from the particular lamp which flares up to which specific group of printing plates the one printing belongs, and can therefore readily sort the envelopes already printed as they leave the machine in the manner required.

The actual displacement of the pad P is effected by a system of levers, connected with the printing lever, whenever the said system of levers carries out a movement relatively to the printing lever. This will be the case, as soon as a lever of the system and which is subjected to frictional action comes to be retained by a pawl released on the magnet serving to control the catch motions having been excited. The subsequent release of the lever system and the retracting of the pad P into the inoperative position takes place in the course of the following working stroke of the printing lever. The arrangement of the pad P at the printing lever may be devised in the manner known.

A construction illustrating the carrying out of my invention is shown by way of example in the drawings annexed to this specification and forming part thereof.

Figs. 1 to 3 are diagrams of the system of electrical connection for a device constructed in accordance with my invention, along with views of the appropriate parts.

Figs. 4 to 8 are side views of the printing lever in different working positions, along

with the system of levers serving for the displacement of the pad, as also the control device for the said system of levers,

Fig. 9 is a plan view of Fig. 8, and

5 Fig. 10 is a bottom view of the printing plates appertaining to two groups.

Referring to Figs. 1 to 8 of the drawings, α is the slide track of an addressing machine along which, on the printing lever being operated, the printing plates b are fed forward as they pass out of a magazine, the addressing machine illustrated belonging to the type in which the printing plates are fed forward by means of a slide member. The printing plates b (Fig. 10) are provided with depending projections c which are preferably pressed directly out of the printing plate. In the form of execution shown it is assumed that the machine is intended for two groups 20 of printing plates; however the machine may be readily adapted to comprise a larger number of groups of printing plates by simply duplicating the arrangement. The subdivision of the printing plates b into the 25 said two groups, is effected by the projections c of the printing plates being staggered relatively to each other, as shown in the case of the two printing plates disclosed by Fig. 10. As will be observed, the projection c of the one group of printing plates is located intermediate the first and the second line of the printing matter thereon, whereas in the other group it is disposed between the 30 second and the third line. Where a further subdivision of the groups is required, additional projections may be arranged outside 35 of the lines.

In the construction shown, the slide track α is provided with only two slots e , within 40 which the projections c of the printing plates b are adapted to glide. At a particular point of the track and that at a certain distance in front of the place where the printing is carried out, angle levers f or f' , 45 respectively, are caused to protrude into the said slots e and against which the projections are adapted to abut. To reliably secure the projections c abutting against the angle levers f , f' , there are provided rollers g 50 lodged in a box i and serving to force the printing plates downward at this particular point. Contact springs k , k' , lodged in the frame of the machine, are adapted to cooperate with the angle levers f , f' (Figs. 1 55 and 2).

Each of the contact levers f , f' is disposed within a circuit within which a line is adapted to run from one of the poles of a source of electric supply to the contact levers f , f' . 60 From the contact springs k , k' there proceed two lines to the switch contacts l or l' respectively, whence the circuit continues to an electromagnet n connected to the other pole of the source of electric supply. With 65 in the branch $k-l$ of the system of connec-

tion there is arranged a lamp m , while similarly within the branch $k'-l'$ of the system there is disposed a lamp m' (Fig. 3).

The result obtained by means of the hereinbefore-described system of connections is 70 as follows:

If the switches l , l' are open and the projections c of the printing plates b come to abut against the contact levers f or f' , respectively, so that in consequence the contact pins o or o' , respectively, will come to make contact with the contact springs k , k' , then, notwithstanding, no closure of the circuit, no excitation of the magnet n will be effected because the circuits are still interrupted at l , l' . If now, however, say, the switch l be closed, then as soon as the projections of the printing plates b abut against the angle lever f , the circuit within which the lamp m as also that within which the magnet n is disposed, will come to be closed, causing the lamp m to flare up and the magnet n to be excited, while the striking of the projections of the other group of printing plates against the angle lever f' will continue to produce no effect whatsoever. 85

Each time the electro-magnet n is excited, the armature p , for its part which has the form of a bent lever (cf. Figs. 4-9) and is pivotally lodged within the frame of the device, is attracted. When the electro-magnet is not excited, the bent lever p bears by aid of a pin q against one of the arms r of a two-armed lever r , s , the arm s of which is loaded by a weight t , whereas the arm r terminates in a pawl u . Upon the axis of the bent lever p there is in addition arranged an arm v , against the extremity of which the pawl w of a bent lever t , y is adapted to bear (Fig. 4). The pawl u of the lever r , s is adapted to cooperate with the end of a two-armed lever z which, with the interpolation of a friction coupling, is pivoted at l to the printing lever 2 of customary type. A system of levers 3, 4, 5, 6, 7, which is pivotally disposed at 8 on the printing lever 2 starts from the other end of the lever z . The end of the arm 7 is connected to a shaft 9, lodged to rotate within the head of the printing lever, on which shaft there may be arranged, for example, the control roller for the pad p , and this in suchwise, that, according to the position assumed by the said roller, the pad P (not shown) will be disposed at a greater or 110 smaller distance from the head of the printing lever 2.

As a result of this arrangement, the printing plate positioned at the place where the printing is to be effected will only then come to make an impression on the pad P being shifted downwards out of its initial position by a rotation of the roller. 115

The manner of operation of the device disclosed in Figs. 4-9 is as follows: 120

The magnet n not being excited, and as a result the pawls acted upon by said magnet assuming the positions shown in Figs. 4 and 5, there will take place no relative movement on the part of the system of levers z , 3, 4, 5, 6, 7 with respect to the printing lever 2 as this latter carries out an up and down motion, so that therefore the pad P will also not be shifted into the printing position, Fig. 4 showing the position of the parts when the printing lever assumes its uppermost position and Fig. 5 the position of the parts when the printing lever assumes its lowermost position.

If now, however, while the platens b are being fed forward, the electro-magnet n come to be excited, that is to say, while the printing lever 2 (Fig. 6) is moving upward, then the lever p will be attracted and release the two-armed lever r, s , the weight t of which latter had so far been unable to overcome the weight of the lever p resting upon the other arm r of the lever. Hence, the pawl u bears up against the end of the lever z and engages the said end, as shown in Fig. 7, as soon as the printing lever 2 has attained its uppermost position. With the view to retaining the lever p in the position into which it has been attracted by the magnet (Fig. 6), the lever x, y , acting under the impulse of its weight, has meanwhile engaged the end of the lever v by means of its projection w (Figs. 6 and 7), so that the lever p will remain in the position disclosed in Figs. 6, 7 and 8, even after the excitation of the electro-magnet n has ceased, and which excitation has in fact only lasted for an instant.

If now the printing lever 2 be moved downward out of its uppermost position, then the lever z will be unable to follow the said movement by rotating about its pivot 1, but will rather be secured in its position by the pawl-provided lever r, s and this counter to the action of the friction coupling arranged between it (i. e. lever z) and the printing lever 2. As a result there takes place in the course of a downward motion of the printing lever 2, according to Fig. 8, a relative movement on the part of the system of levers 3 to 7 with regard to the printing lever, so that on this latter attaining its lowermost position, as shown in Fig. 8, for example, lever 7 will come to assume the position indicated, causing the shaft 9 to be rotated within the head of the printing lever and therewith likewise the pad P to be shifted into the printing position. It will thus be seen that when the parts are in the position shown in Fig. 8, the platen positioned at the place of printing will come to effect an impression.

At the instant of printing, the printing lever 2 draws the retaining lever x, y , according to Fig. 8 by means of a pin 11, fixed

to it by aid of plate 10, back in the direction indicated by arrow 12 into the initial position (Figs. 4 and 5), with the result that the lever p , which for some time has ceased to be retained by the electro-magnet n , will likewise return into its initial position, and in so doing depress the arm r of the lever r, s by means of the pin q so that now the projection u will in its turn release the lever z .

As the printing lever 2 moves upward out of the position illustrated in Fig. 8, the lever z , which is prevented by a pin 13 from continuing to rotate in the direction indicated by the arrow 14, now returns into its initial position relatively to the printing lever 2 as shown in Figs. 4 and 5. However, this return motion of the lever z causes the shaft 9 to rotate backwards and consequently a retraction of the pad P into its initial position, i. e. the position in which no impression is made, whereupon the operation will be repeated provided the next printing plate is again intended to provoke an excitation of the electro-magnet n . In the contrary case, the next-following platen will simply travel across the machine without effecting an impression.

It will be understood that the hereinbefore-described addressing machine embodies the possibility, according to whether the switch l or l' be closed, of causing either the one or the other group of printing plates to be printed, or even all the printing plates travelling across the machine in the event of both switches being closed.

I claim:

1. In a device of the kind described in combination a machine bed, a carrier adapted to move towards and away from said bed, means for permanently keeping said carrier moving, a pad movably connected to said carrier, a printing plate adapted to travel along said bed underneath said carrier, electric means for influencing the position of said pad relatively to said carrier and means connected with said plate for causing said electric means to change the position of said pad relatively to said carrier.

2. In a device of the kind described in combination, a machine bed, a carrier adapted to move towards and away from said bed, means for permanently keeping said carrier moving, a pad movably connected to said carrier, a printing plate adapted to travel along said bed underneath said carrier, electric means for influencing the position of said pad relatively to said carrier and means connected with said plate for causing said electric means to set said pad in operative position on said carrier.

3. In a device of the kind described in combination, a machine bed, a carrier adapted to permanently move towards and away from said bed, a pad movably connected to

- said carrier, a printing plate adapted to travel along said bed underneath said carrier and electric means adapted to be operated by said plate for changing the position of said pad relatively to said carrier.
4. In a device of the kind described in combination, a machine bed, a carrier adapted to permanently move towards and away from said bed, a pad movably connected to said carrier, a printing plate adapted to travel along said bed underneath said carrier, an electric circuit, means in the way of said plate for closing said circuit, electromagnetic means adapted to influence the position of said impression pad inserted in said circuit and means on said plate for operating said closing means so as to cause said electromagnet to change the position of said pad relatively to said carrier.
5. In a device of the kind described in combination, a machine bed, a carrier adapted to permanently move towards and away from said bed, an impression pad movably connected to said carrier, printing plates adapted to travel along said bed underneath said carrier, a plurality of electric circuits, a separate cut-out for each circuit, a contact and electromagnetic means in each circuit adapted to influence the position of said impression pad, mechanical means for closing said contact projecting into the way of said plates and means on each plate for operating one of said mechanical means so as to close a contact, excite an electromagnet and change the position of said pad relatively to said carrier.
6. In a device of the kind described in combination, a machine bed, a carrier adapted to permanently move towards and away from said bed, an impression pad movably connected to said carrier, a plurality of parallel grooves in said bed, a printing plate adapted to travel along one of said grooves, a plurality of electric circuits, a separate cut-out for each circuit, an electromagnet inserted in each circuit adapted to change the position of said pad relatively to said carrier, a contact closing device adjoining each groove and means on said plate for actuating the contact closing device adjoining the groove along which said plate is travelling.
7. In a device of the kind described in combination, a machine bed, a carrier adapted to permanently move towards and away from said bed, a pad movably connected to said carrier, a plurality of parallel grooves in said bed, a printing plate adapted to travel along one of said grooves, a plurality of electric circuits, a separate cut-out in each circuit, an electric lamp and an electromagnet inserted in each circuit adapted to change the position of said pad relatively to said carrier, a contact closing device adjoining each groove and means on said plate for actuating the contact closing device adjoining the groove along which said plate is travelling.
8. In a device of the kind described in combination, a machine bed, a carrier adapted to permanently move towards and away from said bed, a pad movably connected to said carrier, a plurality of parallel grooves in said bed, a printing plate adapted to travel along one of said grooves, a lever system connected with said pad, a plurality of electric circuits, a separate cut-out for each circuit, an electromagnet inserted in each circuit adapted to influence the operative position of said lever system, a contact closing device adjoining each groove and means on said plate for actuating the contact closing device adjoining the groove along which said plate is travelling.

In testimony whereof I affix my signature
HERMANN DEUTSCH.
